UNITED STATES PATENT OFFICE.

CHARLES H. BORDEN, OF HARTFORD, CONNECTICUT.

DIRECTION-INDICATING APPARATUS FOR AUTOMOBILES.

1,114,676.

Specification of Letters Patent.

Patented Oct. 20, 1914.

Application filed February 6, 1913. Serial No. 746,582.

To all whom it may concern:

Be it known that I, CHARLES H. BORDEN, a citizen of the United States, residing at Hartford, in the county of Hartford and State of Connecticut, have invented a new and useful Improvement in Direction-Indicating Apparatus for Automobiles, of which the following is a specification.

This invention relates to an apparatus that is designed to be attached to an automobile, and by means of which an occupant of the car may indicate the direction it is intended to proceed or desired to travel.

The object of the invention is to provide a simple and easily operated apparatus which can be readily attached to an automobile in such manner that the driver or other occupant of the car can instantly plainly indicate to every one ahead and behind whether it is intended to continue straight on or it is desired to make a turn and in which direction the turn will be made. The apparatus has special utility in cities and towns having strictly enforced traffic regulations, but it also is very serviceable wherever traffic is congested or it is desirable to inform others on the road as well as those on the sidewalks the direction of travel which it is intended to take.

In carrying out this invention, movable arrows are provided with means which may be readily attached to the dash, hood, mud guard or side of a car near the front in such position that the indicators may be readily observed from both front and back. These arrows are connected with means arranged adjacent to the hand or foot of the driver of the car in such location that they may be conveniently and quickly moved and caused to point in the intended direction of travel, and they are desirably provided with electric lamps which can be lighted in the night time to more clearly show the position of the indicators. In the preferred form of the invention which is illustrated, there are two arrows provided with electric lamps. These arrows are shown as mounted on brackets attached to the dash in front of the driver's seat and as connected by flexible shafts with either a hand lever arranged adjacent to the steering wheel, or a lever arranged on the foot board in position to be conveniently moved by the foot of the driver. When it is intended to proceed straight on, the arrows point directly ahead. When it is desired

to turn to the left, a movement of the hand lever or of the foot lever to the left will cause the arrows to point to the left, and when it is desired to turn to the right, a movement of the hand lever or foot lever in that direction will cause the arrows to point in that direction and thereby give visual and readily seen signals to a traffic officer or to others in front of the car and also to any back of the car of the direction in which the car will be driven.

Figure 1 of the accompanying drawings shows a front view of the apparatus arranged to be manipulated by the hand of the driver, and attached to the dash of a car with the arrows pointing to one side as when it is desired to make a turn in that direction, in this view the steering wheel post by which the hand operating lever is desirably supported is omitted. Fig. 2 is a side elevation of the same, showing the arrangement of the hand operating lever adjacent to the steering wheel. Fig. 3 shows on larger scale a section of the foot board of a car body and a portion of the mechanism which may be provided when it is desired to turn the arrows by the foot of the driver. Fig. 4 is a plan of the mechanism shown in Fig. 3. In these views the mechanism is designed to turn both arrows simultaneously. Fig. 5 is a view of a part of the mechanism showing the use of an interrupted gear which may be substituted for the continuous gear shown in the previous views, whereby the arrows may be operated independently. Fig. 6 shows on larger scale a section of the mechanism for positively turning the arrows and holding them in the position to which they are turned, this mechanism being a preferred form when the arrows are to be turned positively either by hand or foot through flexible or jointed shafts. Fig. 7 shows a plan of some of the parts of the arrow locking, releasing and turning mechanism with the pieces in the positions occupied when the arrow is locked central or is pointing straight ahead. Fig. 8 shows a plan of the parts shown in Fig. 7 but in the positions occupied when the arrow lock is released and the arrow is about to be turned to one side. Fig. 9 shows a plan with parts broken away of the rotating commutator which bears the electrical contacts of the lamp circuit. Fig. 10 shows a plan of the fixed contacts of the electrical circuit. 11 shows a spiral spring which may be used with the interrupted gear shown in Fig. 5 to insure a quick return to the central position of an arrow which has been independently turned to one side.

The indicators may be mounted on any convenient portion of the car so that they will stand out in a position in which they may be readily seen. In the embodiment of 10 the invention first illustrated, the arrow-supporting bracket 1 is attached by a socket plate 2 to the front of the dash 3. To the outer end of the bracket is fastened a hollow head 4. Rotatably mounted on the head is a cap 5. This cap has arms 6 to which the arrow point 7 is fastened. The arrow point may be made of any suitable material and may be finished any desired color. A screw 8 fastens the cap to an arbor 9 that is free to 15 turn in the head. Secured to the lower end of this arbor is a disk 10 that has a downwardly projecting lug 11 on one side and that has three notches 12 in its periphery. A bolt 13 is normally thrust by a spring 14 so that its point will engage the notches and hold the disk, arbor and cap from moving and thus retain the arrow in the desired position. Below the disk 10 is a disk 15 which 20 has an upwardly projecting lug 16 that normally lies adjacent to and opposite the downwardly projecting lug 11. The disk 15 is secured to an arbor 17 that is fastened to a flexible shaft 18. Between the upper disk 10 and the lower disk 15 is a cam plate 19. This 25 cam plate is fastened to the disk 15 so that when that disk is turned by the flexible shaft the cam will force back the spring bolt and unlock the disk 10. Between the two disks and extending on each side of the lugs that 30 project from the opposing disks are fingers 20 which are normally held together by a spring 21 so as to retain the two lugs in line. When the flexible shaft is rotated, the disk 15 is turned and while the cam is forcing 35 back the locking bolt the lug which projects from the disk 15 moves one of the fingers 20 and places the spring under tension. As soon as the cam has pushed the bolt back far enough to unlock the disk 10, the pressure of 40 the spring against the other finger 20 that bears against the lug which projects from the disk 10 throws that disk and this through the arbor to which it is attached to the cap, turns the arrow in the same direction that 45 the flexible shaft was rotated. After the arrow has been thrown in this manner to approximately 90 degrees, the bolt enters another notch in the disk 10 and locks it so that the arrow is held in that position until 50 the shaft is turned reversely and the bolt again withdrawn and the throwing spring put under tension for moving the arrow in the opposite direction. Between the cap 22 that is screwed into the underside of the 55 head and the lower disk 15 is a spring 23

which places a tension on the parts so as to keep them together and prevent them from rattling.

In the apparatus shown the cap which carries the arrow is provided with a small incandescent lamp 24 and a reflector 25 arranged in the fork at the rear of the arrow so as to throw a light thereon when the lamp is lighted. The leads 26 to this lamp are connected by suitable binding screws 27 to 70 spring contacts 28 that are mounted on an insulating disk 29 which is arranged to turn with the cap. The spring contacts on this movable insulating disk are adapted to engage with contacts 30 secured to an insulating disk 31 that is fixed to the head inside of the cap. Connected with these fixed contacts are circuit wires 32 which are preferably led through the tubular supporting brackets to a switch 33 desirably placed on 75 the dash within reach of the driver of the car, and to a battery 34.

Each of the flexible shafts 18 leads to and is connected with a pinion 35 mounted in bearings on a plate 36 that may be attached 90 to the dash. Engaging with these pinions is a gear 37 on a plate 38 that is rotatably mounted on the supporting plate. This plate, in the form first shown, is connected by a link 39 with the end of a rocker arm 95 40, the arbor of which is connected by universal joints 41 with a shaft 42 that is supported by bearings attached to the steering wheel post 43. On the upper end of this shaft adjacent to the steering wheel is a handle 44 which may be turned for rotating the shaft and through the mechanism described, rotating the flexible shafts and turning the arrows. A segment 45 is desirably mounted 100 on the steering post for retaining the lever 105 in the position to which it is turned.

When it is desired to turn the arrows by means of the foot instead of by hand, the gear plate 38 is provided with a stud 46 which extends into a socket 47 on the under- 110 side of a lever 48 that is provided with a pin 49. The pin 49 is shown as projecting through the foot board 50 so that it may be moved either one way or the other by the 115 foot of the driver whose heel is placed in the rest 51. Turning the foot pin either one way or the other turns the arrows in the same manner that they are turned by the handle, as previously described.

If it is desired to have both of the arrows turn simultaneously, the teeth on the gear plate 38 are arranged so as to always be in mesh with both of the pinions at the ends of the flexible shafts, as shown in Figs. 1 and 4. If it is desired to have the arrows move independently, that is, to only turn the arrow that is on the side to which the car is to be turned, the gear teeth may be arranged as on the plate 52 (Fig. 5), so that 120 they will mesh with but one shaft pinion at 125 130

a time. If such a gear plate as 52 is used, instead of such a gear plate as 38, then a spring 53 (Fig. 11) is arranged in the bottom of the head with one end of the spring slipped upon the fixed stud 54 and the other end of the spring slipped on the movable stud 55. With this arrangement, when the arrow is turned, the spring is placed under tension so that when the arrow is released 10 the spring will quickly return it to central position.

The invention claimed is:

1. An automobile attachment comprising arrows, supports for said arrows adapted to be attached to the sides near the front of a car so the arrows will be visible from front and rear, locking mechanism for retaining the arrows in either of several positions, means for releasing the locking mechanism, flexible shafts which when turned first operate the releasing means and then turn the arrows, gearing for rotating said shafts, and means for rotating the gearing in opposite directions.

2. An automobile attachment comprising arrows, supports for said arrows adapted to be attached to the sides near the front of a car so the arrows will be visible from front and rear, locking mechanism for retaining the arrows pointing forward, means for releasing the locking mechanism, flexible shafts which when turned first operate the releasing means and then turn the arrows, gearing for rotating said shafts, and means for rotating the gearing in opposite directions.

3. An automobile attachment comprising arrows, supports for said arrows adapted to be attached to the sides near the front of a car so the arrows will be visible from front and rear, locking mechanism for retaining the arrows in either of several positions, means for releasing the locking mechanism, flexible shafts which when turned first operate the releasing means and then turn the arrows, gearing arranged to ro-

tate the shafts simultaneously so as to turn the arrows together, and means for rotating the gearing in opposite directions.

4. An automobile attachment comprising arrows, supports for said arrows adapted to be attached to the sides near the front of a car so the arrows will be visible from front and rear, locking mechanism for retaining the arrows in either of several positions, means for releasing the locking mechanism, flexible shafts which when turned first operate the releasing means and then turn the arrows, gearing for rotating said shafts, and means adjacent to the steering wheel for rotating the gearing in opposite directions.

5. An automobile attachment comprising horizontally movable arrows, supports for said arrows adapted to be attached to the sides near the front of a car so the arrows will be visible from both front and rear, locking mechanism for retaining the arrows in either of several positions, means for releasing the locking mechanism, flexible shafts which when turned first operate the releasing means and then turn the arrows horizontally, gearing for rotating said shafts, and means for rotating the gearing in opposite directions.

6. An automobile attachment comprising horizontally movable arrows, supports for said arrows adapted to be attached to the sides near the front of a car so the arrows may be visible from front and rear, yielding means normally holding the arrows pointing forward, flexible shafts and connections for turning the arrows horizontally from side to side, gearing for rotating said shafts coincidentally, means for rotating the gearing in opposite directions, electric lamps rotatable with said arrows, and circuit connections leading to said lamps.
